UNITED STATES PATENT OFFICE

2,434,706

RECIPROCATING CLOSURE FOR COLLAPSIBLE TUBES WITH PARALLEL GUIDE FLANGES

Paul D. Malyszko, Portland, Oreg.

Application March 3, 1944, Serial No. 524,917

1 Claim. (CL 222—561)

1

This invention relates to an improved collapsible tube of such type as is used for marketing and subsequently dispensing toothpaste, shaving cream, and paste-like cosmetics and has reference in particular to the neck and closure construction, the closure being permanently attached to the neck to facilitate operation and to obviate the likelihood of loss, thus accomplishing a result now generally sanctioned by manufacturers, retailers and users.

In carrying out the principles of the invention I have provided a simple, expedient and otherwise useful closure, the latter being of a slide type and so designed and mounted as to expedite handling and manipulation thereof by a single hand of the user.

More specifically, I provide a collapsible tube having a discharge neck with a dispensing port and a slide closure, there being a so-called tongue and groove connection between the neck and the closure.

Other features and advantages of the invention will become more readily apparent from the following description and the accompanying illustrative drawings.

In the drawings, wherein like numerals are employed to designate like parts throughout the views:

Figure 1 is a fragmentary sectional view showing a collapsible tube and an especially constructed discharge neck embodying the closure means constructed in accordance with the specific principles of the instant invention.

Figure 2 is a vertical section at right angles to Figure 1, this being on the plane of the line 2—2 of Figure 1 looking in the direction of the arrows.

Figure 3 is a view like Figure 1 showing the slide closure shoved from right to left to so-called "open" position.

Figure 4 is a top plan view of Figure 3.

Figure 5 is a section similar to Figure 2 but taken on the plane of the line 5—5 of Figure 1.

Referring now to the drawings by distinguishing reference numerals it will be observed that the collapsible body is denoted by the numeral 6 and this is provided with an integral discharge neck 7 closed for the main part by a partition or diaphragm 8, the latter being provided at a predetermined point with a relatively small ejection and clean discharge slot 9. At one end of the partition is a projection 10 constituting a detent or keeper for releasable snap engagement in a keeper seat 11 formed in the adjacent end portion of the slide closure 12. The closure is of gen-

2

eral rectangular block-like form and provided on opposite longitudinal edges with outstanding flanges 13 which constitute keying ribs. The neck is provided with a pair of parallel flanges 14 spaced above the web or partition 8 and defining therebetween channels 15 which constitute keyways for slidable reception of the keys or ribs 13. The central portion of the slide is thickened and rounded off into convex form to provide a riser 16 which also functions as a finger-piece. It will be noted that the riser has its opposite ends somewhat indented as at 17 to facilitate the production of shoulders, that is, push shoulders for reception of the finger to be used in opening and closing the closure. The width of the closure is such that the longitudinal marginal edge portions thereof overlie the top surfaces, that is, the exterior surfaces of the flange 14. There is a formation as at 18 at one end of the slideway which constitutes a stop shoulder. It will be noticed too, that the right-hand half portion of the closure is thickened to define a shoulder 19 to contact with the top shoulder 18. This thickened part 20 rides in slidable contact with the diaphragm 8. Incidentally the part 20 is the essential closure element in that it feeds across the slot 9 to close the same as indicated in Figure 1. At this time the projection or detent 10 snaps into the keeper seat 11. Thus, the coacting elements 10 and 11 serve to limit the sliding movement of the closure 12 in a direction from left to right (see Figure 1) whereas the coacting shoulders 18 and 19 limit the sliding movement in the opposite direction as brought out in Figure 3. Hence, the closure is not only keyed to the neck but its sliding motion in opposite direction is properly checked. Consequently, it is slidably mounted in place against displacement.

It is thought that persons skilled in the art to which the invention relates will be able to obtain a clear understanding of the invention after considering the description in connection with the drawings. Therefore, a more lengthy description is regarded as unnecessary.

45 Minor changes in the shape, size and arrangement of details coming within the field of invention claimed may be resorted to in actual practice, if desired.

Having described the invention, what is claimed 50 as new is:

As a new article of manufacture, a collapsible tube having an outwardly projecting reduced discharge neck, the outer discharge end of said neck being provided with a substantially flat closing 55 diaphragm, said diaphragm having a discharge

port adjacent one end portion and being provided outwardly of said discharge port with an upstanding projection constituting a detent, said diaphragm being provided at an opposite end with a riser constituting an abutment and stop shoulder, the neck outwardly of said diaphragm being provided with parallel outstanding portions formed with inwardly projecting opposed parallel flanges, said flanges occupying a plane overlying the diaphragm, riser, and detent in outwardly spaced relation and defining an open-ended channel-like closure assembling mount and guide tracks for said closure, a closure comprising an elongated block-like body disposed in the channel between the guide tracks and having its inner surface in slidable contact with said diaphragm, said block being of a length corresponding to the length of the channel, the underneath surface of said block being flat and in intimate movable contact with the diaphragm, and one-half portion of said underneath surface being fashioned into a depending lug-like port-closing element, said element also constituting a stop shoulder and being engageable with the first-named stop shoulder, this to limit the sliding movement of the body in one direction, said body being pro-

vided, intermediate its outer top surface with a raised part having transversely curved ends forming finger recesses to facilitate grasping and sliding the body from closed to open position, the opposite longitudinal perimeter portions of said body being provided with channels, the aforementioned flanges snugly fitting into said channels, and said channels defining inner and outer pairs of flanges, the latter having slideable contact with said first-named flanges.
